COMBINATION OVERSHOT ROTARY MILLING-CUTTER.

1,253,015.

Specification of Letters Patent.

Patented Jan. 8, 1918.

Application filed October 8, 1917. Serial No. 195,266.

To all whom it may concern:

Be it known that I, DENNIS L. DRISCOLL, citizen of the United States, residing at Coalinga, in the county of Fresno and State 5 of California, have invented certain new and useful Improvements in Combination Overshot Rotary Milling-Cutters, of which the following is a specification.

The present invention relates to an improved tool for use in the fishing of tools or 10 their supporting pipe strings employed in the drilling of oil wells by the rotary process. In the drilling of oil wells by the rotary process, the bit or drill is attached 15 to the lower end of a string pipe or other support which is rotated and by this rotation the boring of the hole into the oil sands is accomplished. Owing to the extreme 20 depth of some of the drilling operations the pipe string or support becomes very long, and due to its great length often buckles or twists off, and at times when the pipe is removed from the soil or well and the sections thereof are separated to change the 25 drilling tool, portions of it often drop to the bottom of the well and become twisted and bent therein and unless removed it is necessary to either drill around the same or abandon the well.

30 The present invention has for its principal objects to provide a tool particularly designed for removing these broken, separated, or twisted sections of drilling pipe or support from the well, to provide a construction which is adapted for cutting its way over the end of the pipe and to cause the same to pass upwardly through the tool, to provide engaging means on the inner surface of the tool for engaging the pipe to 35

40 assist in raising the same from the hole, or if required, to enable the pipe to be cut free at a point of connection with another section or in the main body portion thereof, to provide a construction wherein the pipe cutting and engaging devices are adapted to 45 pass freely over the pipe on the lowering of the tool and which will immediately engage the same when the tool is drawn upwardly a slight distance over the pipe.

50 With the above mentioned and other objects in view, the invention consists in the

novel construction and combination of parts hereinafter described illustrated in the accompanying drawings, and set forth in the claims hereto appended; it being understood 55 that various changes in the form, proportion, size and minor details of construction within the scope of the claims may be resorted to without departing from the spirit or sacrificing any of the advantages of the 60 invention.

To more fully comprehend the invention, reference is directed to the accompanying drawings, wherein,

Figure 1 is a vertical sectional view of 65 the preferred embodiment of my invention.

Fig. 2 is a transverse sectional view taken on the line 2—2 of Fig. 1.

Fig. 3 is a view in detail plan of one of 70 the cutting and engaging dogs.

Fig. 4 is a view in detail of a modified form of cutting and engaging dogs.

Referring more particularly to the several views of the drawings, wherein like characters of reference designate corresponding parts, 1, indicates a suitable tubular member preferably in the form of a pipe the length of which depends on the number of attached sections which are preferably secured together in the usual manner by 75 threaded collars. In the carrying on of a fishing operation sections are added to the pipe 1, to permit the tool at the lower end thereof to be inserted into the hole or well the required distance. On the lower end of 80 the pipe 1, is threaded as at 2, a body 3, preferably tubular in form, and to the lower end of which is threaded as at 4, a suitable milling cutter 5, preferably of the rotary type, having the cutting teeth 5' on the lower 85 peripheral surface thereof. This cutter is adapted when the tool is lowered into a well and rotated to cut its way over the pipe or support which is to be fished out, thereby enabling the pipe to pass upwardly through 90 the body 3 and supporting pipe 1. The body 3 is formed with suitable vertical guide slots 6, dovetailed in cross-section, and which converge inwardly at their inner or lower ends and are preferably formed at their lower 100 ends with seat portions 7.

Vertically movable within each of these

guide slots 6, is a suitable block or member 8, dovetailed in cross-section and upwardly from each of which through the slots 6, extends a connecting arm 9, each secured at 5 its upper end to a suitable weighted collar 10, thus, it will be apparent, that the connecting arms 9 and collar 10, unite each of the blocks 8. The lower faces of the blocks 8 are provided with seat portions 11, for 10 contacting with and resting on the seat portions 7, of the guide 6, when the blocks are at the lower ends of guide slots 6, and said blocks are also formed with the upwardly beveled surfaces 12, which permits 15 a free upward movement of the blocks when moved laterally by their upward movement in the guide 6 over any object which may pass through the body 3.

The vertical faces 13, of the respective blocks 8, are formed with cutting edges 13' as are the upper surfaces of the horizontal portions 14, of said blocks as at 14', thus when it is found that the pipe to be fished out cannot be withdrawn from the hole in 20 one piece, the weight of the collar 10 after the tool is passed downwardly over the pipe will cause the blocks to engage the side walls thereof and a rotary motion being imparted to the supporting pipe 1 the cutting edges 25 13' will engage the support for the boring tool and sever the same enabling the upper section to be fished out. Should a collar be encountered in this operation and a slight pull be exerted upwardly on the body, the 30 cutting surfaces 14 will engage under the collar and on rotary motion being imparted to the tool mill that portion of the collar coöperating with the lower section, enabling the section immediately above the same and 35 those above it to be withdrawn from the hole. In this construction the greater the upward pull on the member 1 the tighter the blocks 8 are forced into the member engaged 40 thereby, due to the converging of the slots 6. 45 In my construction I provide a milling cutter 5, to assist the tool in cutting its way over the pipe to be fished out and also provide the cutting surfaces 13' and 14' on the blocks 8 for cutting directly into the pipe 50 when the face 13 is employed, or milling under a collar when the face 14 is employed, and said blocks carrying said cutting devices are also adapted due to the converging 55 guide slots to tightly engage the pipe to be fished out on tension being placed on the supporting pipe 1.

If desirable the blocks 8 may be provided with the rotary cutters 15, extending inwardly from the vertical faces thereof and 60 supported on the vertical shaft 16.

By my improved apparatus it will be apparent that where it is found that the rotary drilling tool pipe or support cannot be removed in one operation the same may be

successively cut into several sections and 65 each section as cut removed, the lower edge of the cut section resting on the cutting edge 14, of the respective blocks 8 when the same is lifted from the hole.

Having thus described my invention what 70 I claim as new is:

1. A tool for the described purpose comprising a tubular body, a milling cutter secured to the lower end thereof, and a plurality of vertically movable engaging blocks 75 carried by and projecting beyond the inner surface of said body, each of said blocks provided with a cutting surface on the inner exposed face thereof.

2. A tool for the described purpose, comprising a tubular body, said body provided in its side walls with vertically disposed guide slots converging at their lower ends, a vertically movable block positioned within each of said slots and each formed with a 85 vertical cutting face, and a rotary cutter secured to the lower end of said body with its cutting face projecting annularly from the lower peripheral edge thereof.

3. A tool for the described purpose, comprising a tubular body provided with a plurality of vertically disposed guide slots converging at their lower ends, and a vertically movable block positioned within each of said slots and each formed on its inner exposed 95 face with a cutting surface.

4. A tool for the described purpose comprising a tubular body formed in its side wall with a plurality of vertically disposed guide slots opening at their lower end toward the inner face of said body and converging at their lower ends, a block vertically movable within each of said guide slots and provided with a cutting edge for extending beyond the inner wall of said 105 body, an annular member movable vertically of said body, and a connection extending longitudinally of said guide slots and uniting each of said blocks with said vertically movable member whereby said blocks will 110 move in unison.

5. A tool for the described purpose comprising a tubular body formed with a plurality of vertically disposed guide slots converging at their lower ends, a block vertically movable within each of said guide slots and provided with a cutting edge for extending beyond the inner wall of said body, an annular member movable vertically of said body, a connection extending longitudinally of said guide slot and uniting each of said blocks with said vertically movable member whereby said blocks will move in unison, and a rotary milling cutter secured to the lower end of said tubular body with 120 its cutting faces providing the lower annular wall surface of said tool.

6. A tool for the described purpose, com-

prising a tubular body provided with a plurality of vertically disposed guides converging toward the lower end of said tubular body, a vertically movable member 5 within each of said guides and each provided on its inner exposed face with a cutting surface.

In testimony whereof I have signed my name to this specification in the presence of two subscribing witnesses.
